Application March 22, 1954, Serial No. 417,750

Claims priority, application Germany March 20, 1953

10 Claims. (Cl. 137—620)

This invention relates to a relay for the indirect control or operation of a pressure-operated regulating device, measuring device or other device with the aid of a liquid or gaseous pressure medium the flow of which into or out of the pressure operated system of the device is controlled by nozzle-shaped valves operated by a control member or impulse emitter. The invention has for object an improvement or modification of the invention disclosed in the specification of co-pending application Serial No. 346,507 filed April 2, 1953.

According to the above-mentioned specification there is arranged in a pressure chamber of the relay a nozzle closing member which cooperates with two nozzles (an inlet nozzle and an outlet nozzle) which project into the pressure chamber and have similarly directed openings on which the closure surface of said member rests in the balanced condition of the system, whilst upon actuation by the impulse emitter it is tilted either about the opening of the outlet nozzle so as to open the inlet nozzle, or conversely about the opening of the inlet nozzle so as to open the outlet nozzle, the nozzle about the opening of which the nozzle-closing member is tilted remaining closed or substantially closed. The control movements of the impulse emitter are transmitted from an operating member disposed outside the pressure chamber to the tiltable nozzle-closing member within said chamber via a swinging lever system which projects in a pressure-tight manner into the pressure chamber. The present invention makes such a relay simpler, cheaper and more economical in space. Moreover the sensitivity of the relay is to be increased, as the control forces exerted by the impulse emitter are generally weak.

According to the invention the nozzle-closure member arranged in the pressure chamber of the relay consists of a closure flap which in the balanced condition of the system rests on both openings of the inlet and outlet nozzles, this closure flap being connected by coupling means with a control shaft which is rotatable by the impulse emitter in one or other direction according to its deflecting movement, the linkage permitting, upon angular movement of the control shaft and according to the direction of deflection, lifting of the closure flap either solely from the opening of the inlet nozzle or conversely solely from the opening of the outlet nozzle, while the other nozzle remains closed or substantially closed.

The coupling means may advantageously be constructed in the form of a transverse pin joint. For this purpose the closure flap which cooperates at one side with the nozzles may for example be rotatably mounted at the opposite side about an axle which is advantageously parallel to the surface of the nozzle openings and in turn is carried by a bearing block which is secured on the control shaft, which extends substantially at right angles to the said axle and preferably is in the same plane as the latter. The control shaft may project outwardly through a pressure-tight bearing arranged in the housing of the relay, and may be connected at the exterior with an actuating

2

lever to which the adjusting force of the emitter is applied. It is advantageous to load the closure flap by a spring or the like which is preferably adjustable and which tends to press the flap against the openings of the inlet and outlet nozzles.

In a particularly simple and advantageous form of the invention the coupling means are formed as a spring link. For this purpose it is sufficient to provide, instead of the bearing block employed with the above-mentioned pin joint and the said axle, a torsion spring which is secured at its centre to the control shaft and is connected firmly at both ends with the closure flap. This torsion spring link permits, like the transverse pin joint, a movement of the closure flap upon an angular deflection of the control shaft such that either the inlet nozzle or the outlet nozzle is open whereas in the neutral position both nozzles are kept closed by the flap.

The invention enables the size of the relay to be appreciably reduced since the coupling means require little space and lie practically in the same plane as the closure flap and the control shaft. Moreover there are only a few movable parts and places at which friction can arise, so that the relay reacts with great sensitivity to very small adjusting forces. This is of particular importance for the practical employment of such a device, since the impulse emitter, for example a manometer, a thermometer, a control diaphragm or the like can often exert only relatively small forces.

Some embodiments of the invention are illustrated by way of example in the accompanying drawings.

Figures 1, 2 and 3 show in longitudinal section, transverse section and horizontal section respectively a relay with a transverse pin joint, Figure 1 being a section taken on line I—I of Fig. 3, Fig. 2 being a section taken on line II—II and Fig. 3 being a section taken on line III—III all in the direction of the arrows,

Figures 4 and 5 show in cross section two different positions of deflection of the closure flap,

Figures 6, 7 and 8 show in perspective one of the closure positions, the balanced position, and the other closure position of the closure flap respectively, and

Figures 9, 10 and 11 show in longitudinal section, transverse section and horizontal section respectively a relay with a spring link, Figure 9 being a section taken on line 9—9 of Fig. 11, Fig. 10 being a section taken on line 10—10 of Fig. 11 and Fig. 11 being a section taken on line 11—11 of Fig. 9, all in the direction of the arrows.

The relay comprises a housing 1 which encloses a pressure chamber 2 which is connected via a tube 3 with the pressure operated system of the device to be controlled or actuated. This may for example consist of a regulating valve adjustable by a diaphragm or a piston, a measuring instrument, a control device actuated by a resilient tube or a piston, or the like.

Into the pressure chamber 2 project two similarly directed nozzles 4 and 5 arranged at a definite distance from one another, the nozzle 4 serving as the inlet nozzle and the nozzle 5 as the outlet nozzle, or vice versa.

The openings 6 and 7 of the nozzles 4 and 5 respectively can be closed one at a time or both together by the closure surface 8 of a closure flap 9 mounted in the pressure chamber 2. The closure flap 9 is connected at the side opposite to the closure surface 8 by a coupling means with a control shaft 10 which is rotatably mounted in a bearing 11 arranged in the side wall of the housing. A sealing member, for example a rubber tube 12 drawn partly over the control shaft 10 and partly over the bearing sleeve 11 provides for pressure-tight passage of the control shaft 10 to the exterior. On the outwardly projecting end of the control shaft 10 may be secured a lever arm 13 to which the adjusting force of an impulse

emitter is applied. This impulse emitter may for example be a manometric and thermometric measuring apparatus, a thermostat, a float, an electro-magnet, a diaphragm moved by any hydraulic or pneumatic adjusting force, a piston or the like.

On the closure flap 9 acts a loading spring 14 which for example is adjustable from the exterior by means of a screw 15. The spring 14 tends to press the closure surface 8 of the flap 9 against the openings 6 and 7 of the inlet and outlet nozzles 4 and 5 respectively. The closure surface or surfaces 8 may be covered with a soft and preferably resilient sealing material such for example as rubber.

In the form of the invention illustrated in Figures 1 to 8, the coupling linkage is formed as a transverse pin joint. The closure flap 9 is mounted rotatably about an axle 16 which is carried by a bearing block 17. The axle 16 extends parallel to the nozzle openings 6, 7 in the same horizontal plane as the latter. The U-shaped bearing block 17 is secured at its centre to the inner end of the control shaft 10, which extends at right angles to the axle 16 and in the same horizontal plane as that in which the nozzle openings 6, 7 and the axle 16 lie in their neutral position. In this neutral or balanced position of the relay system the closure flap 9 takes up the position shown in Figures 2 and 7 in which it is pressed under the action of the loading spring 14 against the nozzle openings 6 and 7, so that both the inlet nozzle 4 and the outlet nozzle 5 are closed. In this position the pressure medium for example compressed air can neither enter nor leave the pressure chamber 2, and therefore the pressure system communicating with it. Consequently no adjustment of the associated regulating or measuring device or the like can take place.

If the control shaft 10 is turned by the impulse emitter via lever arm 13 in one direction or the other, the bearing block 17 secured to the control shaft 10 takes the closure flap 9 along with it by the action of the axle 16. This closure flap 9 can however only follow the angular movement by executing a tilting movement about the axle 16, so that its closure surface 8 either rests on the outlet nozzle 5 as shown in Figures 4 and 7 and frees the inlet nozzle 4, or rests on the inlet nozzle 4 and opens the outlet nozzle 5 as shown in Figures 5 and 8. In the first case pressure medium flows through the inlet nozzle 4 into the pressure chamber 2 and increases the pressure in the system, whereas in the latter pressure medium flows out of the pressure chamber through the outlet nozzle 5 so that the pressure in the system is reduced. The other nozzle, i. e. the one on which the closure flap 9 is supported, remains completely or substantially completely closed.

In the preferred form of the invention illustrated in Figures 9 to 11 there is inserted between the closure flap 9 and the control shaft 10 a spring link. For example a torsion spring 18 is secured at its centre to the control shaft 10 instead of the above-mentioned bearing block 17. The two ends of the torsion spring 18 are secured to two lateral projections 19 of the closure flap 9. This torsion spring 18 preferably consists of a flat leaf spring which is so stiff that upon angular movement of the control shaft 10 it does not bend, only the central part of the spring being moved angularly to some extent with respect to its ends. For the rest, the torsion spring 18 operates in the same way as the previously described transverse pin joint so that further explanation of its functioning is unnecessary.

It will be understood that the invention is not limited to the constructions described and illustrated, but includes all embodiments which are within the scope of the invention. For example the closure flap may have a different shape from that shown, the loading spring may engage at different points, and the coupling means may be replaced by equivalent means.

I claim:

1. A relay comprising a pressure chamber, a pressure medium inlet nozzle for said chamber, a pressure medium outlet nozzle for said chamber, the orifices of said nozzles projecting parallel and laterally spaced from one another into the interior of said chamber, a common closure flap adapted to cooperate with said nozzles and being tiltable mounted in said pressure chamber, said closure flap being applied equally to both said orifices of said nozzles in the balanced condition of the relay and being alternatively tiltable about the orifice of said outlet nozzle in order to open the orifice of said inlet nozzle in order to open the orifice of said outlet nozzle, a control shaft for actuating said closure flap, said control shaft being rotatable mounted about an axis extending substantially at right angles to said nozzles and substantially parallel to the tilting axis of said closure flap, said closure flap being connected with said control shaft by means of a transverse coupling link adapted to allow an angular movement of said closure flap about an axis extending substantially at right angles to said control shaft during the tilting movement of said flap under the action of an angular movement of said control shaft.

2. A relay comprising a pressure chamber, a pressure medium inlet nozzle for said chamber, a pressure medium outlet nozzle for said chamber, the orifices of said nozzles projecting parallel and laterally spaced from one another into the interior of said chamber, a common closure flap adapted to cooperate with the orifices of said nozzles and being tiltable mounted in said pressure chamber, said closure flap being applied equally to both said orifices of said nozzles in the balanced condition of the relay and being alternatively tiltable about the orifice of said outlet nozzle in order to open the orifice of said inlet nozzle and about the orifice of said inlet nozzle in order to open the orifice of said outlet nozzle, a control shaft for actuating said closure flap, said control shaft being rotatable about an axis extending substantially at right angles to said nozzles and substantially parallel to the tilting axis of said closure flap, said closure flap being connected with said control shaft by means of a spring link adapted to allow a simultaneous tilting movement and an angular movement about an axis extending substantially at right angles to said control shaft of said closure flap under the action of an angular movement of said control shaft.

3. A relay as set forth in claim 2, wherein said spring link comprises a torsion spring which is connected at its centre to said control shaft and at its ends to the side of said closure flap remote from the closure surface side thereof.

4. A relay as set forth in claim 3, wherein the ends of said torsion spring are connected to two lateral projections of said closure flap.

5. A relay as set forth in claim 2, wherein said spring link comprises a flat torsion leaf spring which is so stiff that upon angular movement of said control shaft there occurs no bending of said leaf spring but only angular movement of the centre of the spring relative to the ends thereof.

6. A relay as set forth in claim 1, wherein said transverse coupling link comprises a transverse pin joint.

7. A relay as set forth in claim 6, wherein said closure flap is mounted, at the side opposite to the closure surface side thereof, for angular movement about an axle which is carried by a bearing block secured to said control shaft, said axle being substantially at right angles to said control shaft.

8. A relay as set forth in claim 1, wherein the closure surface of said flap is covered with resilient material.

9. A relay as set forth in claim 1, wherein said control shaft projects outwardly of the pressure chamber through a pressure-tight bearing arranged in the housing of the relay, the exterior end of said control shaft being connected with an actuating member adapted to apply to an adjusting force.

10. A relay as set forth in claim 1, wherein said closure flap is loaded by spring means tending to press the flap against the orifices of said nozzles.
